UNITED STATES PATENT OFFICE.

JEFFERSON D. METCALF, OF GLOSTER, MISSISSIPPI, ASSIGNOR OF ONE-HALF TO
WILLIAM L. JACKSON, OF GLOSTER, MISSISSIPPI.

JOURNAL-BOX COOLER.

1,064,978.

Specification of Letters Patent. Patented June 17, 1913.

Application filed February 24, 1913. Serial No. 750,897.

To all whom it may concern:

Be it known that I, JEFFERSON D. METCALF, a citizen of the United States, residing at Gloster, in the county of Amite and State 5 of Mississippi, have invented certain new and useful Improvements in Journal-Box Coolers; and I do hereby declare the following to be a full, clear, and exact description of the invention, such as will enable others 10 skilled in the art to which it appertains to make and use the same.

My invention relates to new and useful improvements in car journal boxes wherein a cooling device is applied to prevent the 15 said journal boxes from becoming overheated and causing what is called a hot box.

Heretofore it has been the practice to pack cotton waste and oil around the axle of the car wheels to keep the same lubricated 20 and considerable trouble has been experienced by the bearing becoming hot and the waste starting to burn after the oil supply has been substantially exhausted. There is 25 caused considerable delay and expense both in time and the cost of replacing the journals. With my new device, the journal box will be kept cool at all times and the evaporation of oil will be less rapid so that the 30 car axle will be lubricated for a much longer period of time than a journal box of the ordinary construction.

The object of my invention is to provide a device which will be adaptable to any journal box now in use without the necessity of 35 preparing the journal in any particular way other than drilling a hole through the side thereof.

It has been the practice heretofore to form a journal with funnels extending laterally 40 therefrom which are adapted to cool the bearing, but inasmuch as there are a great number of cars in use at the present time which are not provided with these funnels, my invention will place this method of cooling 45 within the reach of all cars now in existence without the necessity of replacing each journal box as would be necessary with the patents heretofore issued.

With the above, and other objects in view, 50 I will now proceed to describe my invention more fully in the annexed specification and drawings, in which,—

Figure 1 is a section of the journal box showing my invention applied thereto; Fig. 55 2 is a detail perspective of a fragment of

my invention showing the sleeve attached to the clamping members which may be applied to the side of a journal box; Fig. 3 is an end elevation of the funnel, and Fig. 4 is a detail of the adjusting ring. 60

Referring more particularly to the drawings, 1 indicates generally a car journal box; 2 is a frame having projections 3 formed at each end which are adapted to receive the clamping bolt 4. This frame is substantially 65 rectangular in shape and is provided at each side thereof with an outwardly projecting sleeve 5, being cut away, as shown at 6. Slidably mounted in the sleeve is a funnel 7 having a tubular stem 8 externally 70 threaded which is adapted to communicate with the interior of the journal box 1. At the mouth of the funnel 7 I preferably provide a wire netting or filtering means 7'. 75

Rotatably mounted between the sections of the sleeve 5 I provide a ring 9 which is internally threaded to co-act with the threads on the stem 8 of the funnel 7 and adjust the same to the necessary position in the journal box. Suitably spaced around the periphery 80 of the ring 9 are grooves 10 which are adapted to receive a spanner or other wrench to provide for the turning of said ring in adjusting the funnel. In the edges of the ring 9 I also provide recesses 11 which are 85 adapted to register with recesses 12 in the sleeve 5 and receive a pin or other locking means and thereby prevent the ring from being accidentally turned.

The frame 2 is composed of three sections, 90 two L-shaped sections indicating 13 and 14 and one U-shaped section, as indicated at 15. These sections are joined together by means of flanges 16 which are connected by means of bolts or rivets 17. 95

In operation, when it is desired to place my improvement on a car journal box of the ordinary construction, holes are drilled in the sides of the journal box and the frame 2 clamped around the said journal box in 100 such a manner that the projecting sleeves 5 will register with the aforesaid holes. The stem 8 of each of the funnels 7 is then inserted in the sleeve 5 through the rings 9 which are turned until the funnel is brought into the 105 proper relation with the holes in the sides of the journal box. A pin or other fastening means is then inserted in the registering recesses 11 and 12 and the rings are thereby prevented from turning and forcing the 110

stems 8 of the funnels 7 out of the proper relation with the holes in the journal box.

While in the foregoing I have shown and described the preferred embodiment of my invention, I wish it to be understood that I may change the particular arrangement of the parts without in any way departing from the scope of the claim annexed.

Having thus fully described my invention, 10 what I claim is:—

In combination with a journal box, a cooling device, comprising, a frame comprising two substantially L-shaped members and one substantially U-shaped member having 15 sleeves extending therefrom, flanges extending from the sides of said sleeves and adapt-

ed to be clamped firmly together, rings intermediate the ends of said sleeves and communicating with the interior thereof, threads internally of said rings, funnels having externally threaded stems adapted to coöperate with the aforesaid internally threaded rings whereby said funnels may be adjusted with relation to the journal box, and means for clamping the whole firmly to the sides of 25 a journal box.

In testimony whereof I affix my signature in presence of two witnesses.

JEFFERSON D. METCALF.
